(57) **CLAIM**

The ornamental design for a visor pouch, as shown and described.

DESCRIPTION

FIG. 1 is a perspective view showing the new design.

FIG. 2 is a top plan view of the new design.

FIG. 3 is a right side elevational view of the new design.

FIG. 4 is a front elevational view of the new design.

FIG. 5 is a bottom plan view of the new design.

FIG. 6 is a left side elevational view of the new design, and is also a mirror image of FIG. 3.

FIG. 7 is a rear elevational view of the new design.

FIG. 8 is a perspective view showing the new design, mounted on a standard passenger vehicle visor; and,

FIG. 9 is an alternate perspective view of the new design, mounted on a standard passenger vehicle visor.

FIG. 10 is a bottom plan view of the new design.

The broken lines showing a card are for the purpose of illustrating environment and form no part of the claimed design.
